UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,064, dated September 9, 1902.

Application filed July 29, 1902. Serial No. 117,583. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading feature of the design consists in a frame the sides and cross-piece of which have a molded outer edge or border and a plain inner edge. The bottom of each side piece is ornamented with a sunken panel, from which spring and extend to the top conventional representations of stalks of grain. The cross-piece is in the shape of a hood, which has at its center a wreath bearing streamers, through the knot of which extend in opposite directions other stalks of grain inter-

woven with sprays of flowers. The summer front, inclosed by the frame, has a molding extending around it near its outer edge and a central oval panel, bearing the representations of two flaming hearts skewered by an arrow. Extending from the top of the panel are streamers and garlands of flowers, the latter being caught up at the sides by scrolls overhanging the panel. Extending beneath the summer front for the width thereof is an ornamented open-work frame.

I claim—

The ornamental design for a fireplace-front as herein described and shown.

In testimony whereof I have hereunto set my hand in the presence of two subscribing witnesses.

THOMAS M. DUDGEON.
